Primary Examiner — Karen E Eldridge Powers(74) *Attorney, Agent, or Firm* — McAndrews, Held & Malloy, Ltd.(57) **CLAIM**

The original ornamental design for a thong gusset, substantially as shown and described.

DESCRIPTION

FIG. 1 is a perspective view of a thong gusset of the present invention, as it may be used in an undergarment (the broken lines shown on the thong gusset and on the undergarment represent unclaimed features);

FIG. 2 is a plan view of the claimed thong gusset design;

FIG. 3 is a front elevational view of the claimed thong gusset design;

FIG. 4 is a rear elevational view of the claimed thong gusset design; and,

FIG. 5 is a right side elevational view of the claimed thong gusset design (the left side elevational view is a mirror image thereof).

1 Claim, 2 Drawing Sheets(56)
